DEGENERATIVE PLATE CIRCUIT DETECTOR
NETWORKPaul O. Farnham, Boonton, N. J., assignor to
Radio Corporation of America, a corporation of
Delaware

Application March 1, 1935, Serial No. 8,864

2 Claims. (Cl. 250—27)

My present invention relates to signal detector networks, and more particularly to a degenerative detector of the plate rectification type.

The ideal type of signal-demodulator network for a radio receiver, and particularly a receiver operating in the broadcast range, is one that has a substantially linear signal input—signal output characteristic up to 100% modulation of the carrier. As has been well known in the past, such ideal demodulation performance is difficult to secure. As a matter of fact various demodulation devices have been proposed in the past, and, in each case, compromises of various factors have been necessitated. For example, the diode type of demodulator has been utilized to approximate linear demodulation, but there are various disadvantages inherent in diode detection circuits. Again, the detection characteristic of a grid leak detector possesses a linear portion, but unfortunately the latter covers only an extremely weak signal range. Demodulators of the plate rectification, or biased, type have been proposed for use to secure linear detection, but such a linear characteristic is secured only up to some 50 to 70% modulation of the carrier.

Now, in modern broadcast reception there is a positive need for a demodulation device which will have a substantially linear detection characteristic up to 100% modulation of the carrier. Such a positive need exists because of the present demand in broadcast radio reception for radio receivers which will be capable of reproducing with a high degree of fidelity the highly efficient modulation of carrier waves at broadcasting transmitter stations. It is obvious that regardless of the efficiency of such modulation, at the broadcast transmitter, such high fidelity transmission will be wasted unless the broadcast receiver is provided with a device which is capable of demodulating the received carrier wave in such a fashion that the demodulation characteristic is linear up to 100% modulation of the carrier.

The various demodulation devices referred to above are not readily adapted to this purpose, and may be said to be highly unsuitable for high fidelity demodulation. Accordingly, it may be stated that it is one of the main objects of my present invention to provide a radio frequency signal demodulator network which possesses a substantially linear detection characteristic up to 100% modulation of the received carrier, and which will additionally possess considerable advantages over a diode demodulation network, the latter having been understood by those skilled in the

art up to the present time as approximating most nearly the aforesaid linear characteristic.

Another important object of the present invention is to provide a signal-detector circuit having a substantially linear characteristic up to 100% modulation of the carrier, and which detector circuit differs structurally from the well known type of plate rectification detector solely in a few extremely simple circuit changes.

Another object of the invention is to provide a degenerative signal detector of the plate rectification type which essentially comprises a tube having, in addition to the usual cathode, grid and anode, a grid biasing impedance connected between cathode and ground, the biasing impedance being so electrically associated with the input and output circuits of the detector that degeneration of audio voltage occurs between the control grid and cathode of the detector tube with the result that the detector circuit has imparted to it a substantially linear demodulation characteristic up to 100% modulation of the received carrier.

Still another object of the invention is to provide a degenerative plate circuit detector of the triode type, wherein the cathode circuit of the detector includes a grid bias resistor, the resistor being free of any by-passing of any audio voltage, and a substantial audio voltage being developed across the aforesaid bias resistor.

Still other objects of the invention are to improve generally the efficiency of detection in radio receivers, and more especially to provide a high fidelity detection system which will not only be simple and economical in construction, but reliable in operation, and readily assembled in a radio receiver of modern construction.

The novel features which I believe to be characteristic of my invention are set forth in particularity in the appended claims, the invention itself, however, as to both its organization and method of operation will best be understood by reference to the following description taken in connection with the drawing in which I have indicated diagrammatically a circuit organization whereby my invention may be carried into effect.

In the drawing:

Fig. 1 schematically shows a radio receiving system embodying the present invention,

Fig. 2 graphically shows the characteristics of the detector network embodying the present invention.

Referring now to the accompanying drawing, Fig. 1 schematically shows my present invention embodied in a conventional type of radio re-

ceiver. Since the present invention is directed to the electrical characteristics of the signal demodulator of the receiving system, the remaining networks of the receiver have been conventionalized, and a brief description will be given with respect to these remaining networks in order to explain the type of receiver in which the present invention is particularly adapted to function.

The receiving system may be of the so-called high fidelity type, which is to be utilized for broadcast reception of modulated carrier waves efficiently modulated up to 100%. It is to be understood, however, that the invention is not limited to such high fidelity receivers, but is of general use where it is desired to have a highly efficient detection network.

The receiving system shown in Fig. 1 generally comprises a source of signals 1, and this source may be the usual grounded antenna circuit, or it may comprise any of the well known types of signal collectors used on automobiles, and it may even comprise a radio frequency distribution line as used in hotels and apartment houses. The collected side band modulated carrier waves are impressed upon the radio frequency amplifier section 2 of the receiver. This section of the receiver may comprise a plurality of cascaded stages of tunable radio frequency amplification; or it may consist of the radio frequency amplifier, first detector and intermediate frequency amplifier of a superheterodyne receiver. In any case there will be impressed upon the resonant input circuit 3 of the demodulator, the amplified modulated carrier waves, at carrier frequency or intermediate frequency. If the receiver is of the tuned radio frequency type, then the numeral 4 designates a continuously variable tuning condenser which is uni-controlled with the variable condensers of the preceding amplifier stages.

On the other hand if the receiver is of the superheterodyne type, then the numeral 4 designates a fixed condenser which tunes the resonant circuit 3 to the operating intermediate frequency. The detector network demodulates the modulated carrier waves, and in the output circuit thereof there is produced the audio voltage which is impressed upon the succeeding audio frequency transmission network. The latter network may comprise one, or more, stages of audio frequency amplification, and the audio output of the last audio amplification stage may be impressed upon any desired type of reproducer. As stated heretofore, the present invention is particularly adapted for high fidelity broadcast receivers, and for this reason it will be understood that the various units of the receiver may be designed in such manner that they are best suited for high fidelity broadcast reception. Such design is well known to those skilled in the art at the present time, and it is unnecessary to explain the electrical construction of the various networks of the system other than the detector network, in this specification.

Considering, then, the detector network it will be seen that it comprises an electron discharge tube 5 of the triode type. Of course, the invention is not limited to tubes of the triode type since any other well known type of tube may be used; for example, a shielded tetrode or pentode may be used. The tuned input circuit 3 of the detector is connected between the signal input grid 6 and the cathode 7, the low alternating potential side of circuit 3 being connected to the cathode 7 through a condenser C_g . The operat-

ing direct current bias for the grid 6 is obtained by disposing in the cathode lead of the tube the resistor R_c , the low alternating potential side of circuit 3 being connected to the negative side of the grid bias resistor through a path which includes resistor R_g .

The anode 8 of the detector tube is connected to a suitable source of positive potential E_B through a path which includes the plate circuit load resistor R_B . An audio by-pass condenser 9 is connected in series with the plate circuit load resistor, and the audio voltage E_a is derived from across the plate circuit load resistor R_B and condenser 9. The carrier input applied to the input electrodes of the detector tube 5 is denoted in Fig. 1 by the symbol E_o ; the grid bias voltage developed across resistor R_c is denoted by the symbol E_c , and the detector plate current is denoted by the symbol I_p . A radio frequency by-pass condenser C_p is connected between the cathode side of bias resistor R_c and the anode 8 of the detector tube.

Superficially the circuit arrangement of the detector network in Fig. 1 would seem to resemble to a great extent the familiar plate circuit detector which operates on the lower bend of the plate current-grid voltage characteristic. The bias voltage developed by the flow of plate current through the bias resistor R_c automatically rises as the carrier input E_o increases. The usual method of operating such a plate circuit detector, however, is to completely by-pass the bias resistor R_c with a shunt condenser across it, the function of the condenser being to by-pass all significant audio frequencies.

The purpose of such a conventional audio frequency by-pass condenser in a biased detector is to prevent the degeneration of audio voltage between the control grid and cathode of the detector tube which would occur if substantial audio voltage were permitted to be developed across the bias resistor R_c . In such a conventional type of plate circuit detector, the variation of output audio voltage E_a with percentage modulation on the input carrier voltage E_o is linear only up to some 50 or 70% modulation. In other words, it is entirely unsuitable for the objects and purposes of the present invention wherein it is desired to greatly extend the linear detection characteristic with respect to higher percentage modulation on the received carrier.

According to the present invention, however, and as shown in the detector network of Fig. 1, the usual shunt audio by-pass condenser connected across the cathode bias resistor is entirely eliminated. The network R_g-C_g prevents carrier degeneration if R_g is large with respect to $1/wC_g$ for the carrier frequency; since any carrier frequency output voltage due to plate current of carrier frequency flowing through R_c will then produce a negligibly small voltage across C_g which is in the control-grid cathode circuit. Of course, in Fig. 1, the presence of C_p prevents most of the carrier frequency plate current from flowing through R_c . There is a degeneration of carrier frequency not affected by the R_g-C_g network due to the presence of a plate to control grid capacity in the triode of Fig. 1 in combination with the capacitive plate load, C_p , for carrier frequency, and for this reason C_p should be large compared with the plate to grid capacity of the detector, but yet small enough to insure that most of the audio plate current flows through R_B and R_c . A good practical an-

swer for this design is to use a shielded tetrode, or pentode, detector tube.

As a result of this extremely simple change in the conventional biased detector circuit a certain degree of sensitivity of the detector is sacrificed due to the audio degeneration caused by the audio voltage developed across the bias resistor R_e , but on the other hand there is provided a detector device that has a substantially linear detection characteristic up to 100% modulation on the received carrier. In this respect the degenerative biased detector of the present invention will greatly resemble a diode detector operated in an efficient manner, but the present detector network possesses the following advantages over a diode detector:

1. No lossing of carrier input tuned circuit.
2. Less critical circuit conditions than those which must obtain in a diode detector to prevent distortion at high percentage modulation. It is pointed out, in connection with this advantage, that the audio output impedance of a diode detector must be kept substantially equal to the direct current resistance of the leak which is employed.
3. The sensitivity of the present detector network is somewhat higher than that of a diode detector.

From an electrical viewpoint the audio voltage developed across R_e when impressed between input electrodes 6 and 7 is of such phase as to produce across the output resistor R_B an audio voltage of opposite (or degenerative) phase to the voltage normally produced across R_B by the detection process. In Fig. 2 there is furnished a graphic analysis of the characteristics of a degenerative plate circuit detector according to the present invention. There is shown in Fig. 2 a family of curves secured by plotting E_o as abscissae against I_p as ordinates. The family of curves is secured by using different values of bias voltage E_c .

If the bias resistor R_e is by-passed for modulation frequencies, as in the conventional and well known type of plate circuit detector, operation of the detector circuit takes place along the solid line curves such as A—A' for both unmodulated carrier waves and for modulated carrier waves. It should be particularly noted that by eliminating the by-passing of audio voltages around the bias resistor R_e , the modulated carrier input may rise to higher values without drawing grid current than it could if the bias resistor R_e were by-passed.

This is explained by the fact that at that part of the modulation cycle at which the carrier input amplitude is a maximum, the instantaneous bias developed across the bias resistor R_e (D. C. plus audio) is impressing a maximum negative bias on the control grid. Hence this constitutes an additional advantage, since it is possible to handle modulated carrier inputs of relatively high amplitude without drawing grid current, and yet demodulate the modulated carrier wave in a substantially linear fashion up to 100% modulation. Such operation cannot be secured with the conventional type of biased, or plate circuit, detector.

The general arrangement of Fig. 1 is capable of yielding greater linearity of audio output up to 100% modulation working along curve C over the modulating cycle than the previous arrangements working over such curves as A—A'. This may be seen by inspection of Fig. 2, remembering that 100% modulation means that the value of

carrier amplitude goes to zero during the modulating cycle. The operating path of curve C is more linear and less sensitive than that of A—A' because the audio voltage impressed on the input electrodes is of such phase as to subtract from the audio output voltage. Due to the saturation effects in the plate current curves of type A—A'; and due to the curvature of the bottom of these curves, it is clear that for high percentages of modulation approaching 100% they will give less linear operation than curve C. Consider operation with an unmodulated or average carrier amplitude of $E_o=10$ volts. Working on A—A' there is experienced non-linearity and severe distortion for modulation percentages in excess of about 60%, corresponding to a maximum carrier amplitude over the modulating cycle of $E_o=16$ volts; whereas operation along C will give linearity up to 100% modulation, maximum carrier amplitude of 20 volts and minimum carrier amplitude of zero.

In general, the higher values of R_e will permit higher carrier levels on the detector grid before overload is reached due to grid current. In Fig. 1 the values of C_g — R_g should be such that substantially all the audio voltage developed by plate current through R_e is impressed upon the input electrodes 6, 7. For an intermediate frequency of 200 kc. impressed at E_o typical constants given merely by way of illustration, for the circuit of Fig. 1 are as follows:

$$\begin{aligned} R_B &= 50,000 \text{ ohms} \\ R_c &= 50,000 \text{ ohms} \\ R_g &= 100,000 \text{ ohms} \\ C_g &= 0.1 \text{ microfarad} \\ C_p &= 500 \text{ micromicrofarads} \end{aligned} \quad 35$$

It should be mentioned that the audio output E_a may be obtained wholly across R_c , in which case R_B would be made equal to zero; or, by making $R_B=R_c$ a push-pull audio amplifier may be fed, one grid being connected (for audio) to the cathode (7), the other grid (for audio) to the plate (8), while the cathodes of the push-pull stage are at the same audio potentials as the end of R_c which is not connected to (7).

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. A radio frequency signal demodulator network which possesses a substantially linear detection characteristic up to 100 per cent modulation of the receiver carrier, comprising a vacuum tube having cathode, grid and plate electrodes; a tunable input circuit having its high potential terminal connected to the grid and its low potential terminal connected to the cathode, said last mentioned connection including a condenser having a low impedance to carrier frequencies, a grid biasing resistor having one end connected to the common terminal between one side of said condenser and the cathode, and a second resistor having one end connected to the common terminal between the other side of said condenser and the tuned circuit, the other ends of said resistors being connected to the low potential end of the network, the values of said resistors being such that degeneration of audio currents developed across the biasing resistor

55

100

occurs while degeneration with respect to carrier currents is prevented.

2. A detecting system comprising a space discharge device having a cathode, an anode and a control grid, a source of signal modulated carrier waves connected to the grid circuit of said space discharge device, an output circuit including a constant source of positive potential connected to the anode, means for biasing the grid to a negative potential sufficient to prevent the

10

flow of grid current during normal operation; said biasing means also providing a purely resistive load which is selectively coupled by conductive coupling at signal frequencies both to the grid circuit and to the anode circuit in such relation to each that a change of potential across the load has compensatory effects upon said two circuits. 5
